SIGNAL

Okla H. Hershman, Indianapolis, Ind., assignor to
 Star-Lite Marker Company, Inc., Indianapolis,
 Ind., a corporation of Indiana

Application April 10, 1934, Serial No. 719,815

12 Claims. (Cl. 40—130)

It is the object of my invention to produce a highway warning signal which will be effective in use, especially at night, and which can be simply and economically manufactured. More specifically, it is my object to produce a warning signal which will embody a plurality of light-reflecting units, each comprising a lens and reflector, but to eliminate the necessity for individually mounting said reflecting units upon a background which must be especially constructed to support the reflecting units in the positions necessary to display the desired signal.

In carrying out my invention, I mount the reflecting units on an articulated flexible chain which can be cut to or made in any desired length and which can be bent into any desired pattern. The chain carries means by which it can be secured to a support in any desired position or form, the chain automatically providing for the proper spacing of the reflecting units.

The accompanying drawings illustrate my invention: Fig. 1 is a fragmental elevation of a warning signal comprising a support or background upon which lengths of my chain are arranged to form letters; Fig. 2 is an elevation of a warning signal comprising a background-forming support upon which a standard form of turn-signal is displayed; Fig. 3 is an enlarged front elevation of a section of chain; Fig. 4 shows the chain in plan; Figs. 5 and 6 are elevations of modified forms of the chain; Fig. 7 illustrates a further modification; Fig. 8 is an elevation of a means which may be employed in mounting the chain upon a support; Fig. 9 is a section on the line 9—9 of Fig. 8; Figs. 10 and 11 are, respectively, an elevation and a plan view of a modified form of chain; Fig. 12 is a section on the line 12—12 of Fig. 10; and Fig. 13 is a fragmental sectional view showing a modified form of means for attaching the chain of Figs. 10 and 11 to a support.

The chain shown in Figs. 1 to 4, 8 and 9 comprises a plurality of links each composed of a pair of spaced side bars 10 and 11, adjacent links being secured together by means of shouled rivets 12, all in a general way similar to the construction of power transmission chain. In each link of the chain thus formed there is mounted a reflecting unit 13. Details of the reflecting unit are not illustrated, as such devices are on the market and well known.

In general, they comprise a casing having a lens in one end and a light reflector inside. While I prefer this general type of light-reflecting unit, I do not limit myself to it. In the chain

shown in Figs. 3 and 4, the side bars 10 and 11 are of a generally square shape, the rivets 12 passing through the holes in opposite corners of the squares. On one side of the chain, shown in Figs. 3 and 4 as the rear side, the laterally projecting corners of the side bars are provided with holes 14 for the passage of nails or screws by means of which the chain can be secured in any desired position against a plane-faced support 16. For convenience, the laterally projecting corners of the side bars on the opposite side of the chain may be cut away as indicated at 17 to uncover the holes 14.

The chain formed as above described may be used in many ways. As shown in Fig. 1, it is used to form letters constituting a warning signal. In Fig. 2, I have shown a signal formed of a plurality of links of chain arranged to form an arrow. Another use of the chain lies in the outlining of obstructions such, for example, as bridge abutments.

If the support 16 upon which the chain is mounted is of wood or of similar material it need not be specially prepared for its function as a support for the chain. The chain is merely disposed upon it in the desired conformation and secured in place by nails or screws which pass through the openings 14 into the support. However, should it be desired to make the support 16 of metal, it may be convenient to prepare it to support the chain in any of a plurality of positions to give any of different signals. For example, as shown in Fig. 2 the chain is arranged to display the customary signal for a left turn, the support 16 being perforated to provide for the passage of screws or rivets by which the chain is held in place. As indicated at 18, the support 16 may be provided with an auxiliary set of openings by means of which the tail of the arrow formed by the chain may be bent in the opposite direction from that shown in Fig. 2. By using the set of openings 18 and by inverting the support 16, the signal presents the customary indication of a right turn. By providing additional sets of auxiliary openings, the same support with the same chain may be used to indicate sharp turns or gradual turns or reverse curves.

Instead of securing the chain to a support by nails, screws, or rivets passing through the holes 14, as previously set forth, other expedients may be employed. For example, I may provide the chain at intervals with projections adapted to pass through and be secured in holes in the support. Such an arrangement is indicated in Fig.

4 where the projections referred to are formed as extensions 12' of the rivets 12, such extensions passing through holes in the support 16. By way of example, I have shown the rivets as secured in place by having the rear ends of the projecting portions 12' riveted against the back face of the support.

In situations where the chain is employed to outline an obstruction, such as a bridge abutment, the method of attachment illustrated in Figs. 8 and 9 may be employed. In that arrangement the chain is mounted through the medium of a mounting member 20 having a T-slot into which the chain is fed by longitudinal movement, the light-reflecting units 13 projecting outwardly through the slot, and the side bars 11 on the back side of the chain serving to retain it in place. The mounting member may be formed in a number of different ways, that shown in the drawings comprising a back 25 and two guide-members 26, the latter being offset along longitudinal lines so that spaces are provided between the offset portions and the back 25 for the reception of the side bars 11. The back 25 and guide members 26 are conveniently formed of metal and secured together as by means of spot welding. A series of holes 28 along each edge of the mounting member is provided for the passage of bolts or screws by means of which it may be secured in place. The chain may be held in place in the mounting member by bending the offset portions of the guide members into contact with the back 25 immediately beyond the ends of the chain.

The chains so far described are arranged with the axes of the reflecting units perpendicular to the plane of flexibility of the chain. This is satisfactory in situations where the surface of the support against which the chain is fastened is plane and normal to the direction from which the signal is to be viewed. It may be desirable in some cases to dispose the axes of the reflecting units in the plane of flexibility of the chain, as indicated in Fig. 6. In such an arrangement, the links of the chain are formed by side bars 10' interconnected by rivets 12, each link carrying a reflecting unit 13 disposed with its axis perpendicular to the axes of the rivets 12. Such a chain could be wrapped around or otherwise secured to a tree or a pole which might be considered as constituting a traffic hazard.

In the chain illustrated in Fig. 5 links of the type shown in Fig. 6 alternate with links of the type shown in Fig. 3. Such a chain would have a wide variety of possible applications.

In Fig. 7 I have indicated side bars or spacing members 31' different in shape from the square side bars in Fig. 3 and having the advantage that they permit the chain to be bent at a sharper angle. Instead of being square, the side bars or spacing members 31' of Fig. 7 are generally circular, and each of them is provided with a series of spacing ears 31', one pair of opposite ears being used to receive the rivets 12 and the other pair being provided with holes 14 for the passage of screws or nails by which the chain may be held in place.

In the type of chain illustrated in Figs. 10 to 13 inclusive, the reflecting units 13, instead of being mounted in the middle of the links, are mounted at the points where adjacent links are connected and, in fact, serve instead of the rivets 12 as the interconnection between adjacent links. To this end, each reflecting unit comprises a body 35 and an enclosing shell 36, the rear end

of the body being provided with a projecting stud 37 and the opposite end with an outwardly extending annular flange 38. The front side bars 39 of the chain are clamped between the flange 38 and the front end of the shell 36, while the side bars 40 on the rear side of the chain are clamped between the base of the casing 36 and a nut 41 on the stud 37.

Two different arrangements are illustrated in Figs. 10 to 13 inclusive for holding the chain to the support 16. In the arrangement illustrated in Figs. 10, 11, and 12, the rear side bars 40 of the chain are provided at intermediate points with laterally extending ears 42 having holes for the reception of screws 43 which enter or pass through the support 16. Preferably, the ears 42 are offset rearwardly so that they may be seated in contact with the support 16 while still providing space for the nuts 41. It is not necessary that every link of the chain be provided with ears 42, such ears being shown only on the outer side-bars of the chain.

In the arrangement illustrated in Fig. 13, the studs 37 are made long enough to project through the support 16 in order to receive a nut 45 on the back of such support. When this arrangement is used, the ears 42 may be eliminated.

The chain shown in Figs. 10 to 13 has the advantage that the rivets, as separate parts, may be eliminated, their place being taken by the reflecting units. In addition, by tightening the nuts 41 the side bars of adjacent links are clamped together and the chain held in a definite configuration.

The various chains shown in the drawings are of light construction and are intended solely for use as warning signals. My invention contemplates, however, that if desired the chain may be of sufficiently heavy construction to serve as a barrier, the presence of which would be clearly indicated at night by the spaced reflecting units.

I claim as my invention:

1. A device of the class described, comprising a support, an articulated chain having a plurality of pivotally connected links, and light-reflecting units carried by said links, said chain being provided at intervals with means for securing it to said support, said light-reflecting units being disposed with their axes alternately perpendicular and parallel to the axes of pivotal connection of the links.

2. A device of the class described, comprising a plurality of light-reflecting units, a spacing member in which each of said light-reflecting units is mounted, said spacing members being pivotally interconnected in series, and means carried by said device for securing it to a support.

3. A device of the class described, comprising a chain formed of a plurality of pivotally interconnected links each having a pair of laterally spaced side bars, and light-reflecting units mounted in intermediate positions in said links, the side bars on one side of said chain projecting laterally beyond the side bars on the other side, said projecting portions being provided with openings for the passage of chain-mounting members.

4. A device of the class described, comprising a chain formed of a plurality of pivotally interconnected links each having a pair of laterally spaced side bars, and light-reflecting units mounted in spaced relation on said chain, the side bars on one side of said chain projecting laterally beyond the side bars on the other side, said projecting portions being provided with

openings for the passage of chain-mounting members.

5. A device of the class described, comprising a plurality of light-reflecting units, a spacing member in which each of said light-reflecting units is mounted, said spacing members being pivotally interconnected in series, and a supporting member having a longitudinal groove, said spacing members having laterally projecting portions adapted to be received in said groove.

6. A device of the class described, comprising an articulated chain, a series of light-reflecting units mounted on said chain in spaced relation, and a mounting member provided with a T-slot, said chain having provisions receivable in said T-slot to hold said chain in position in said mounting member.

7. A reflector button assembly comprising a plurality of reflector button housings, oppositely disposed laterally extending ear portions on each housing, means joining said housings together through said ear portions and reflector buttons positioned within said housings and partially exposed.

8. A marking strip for forming and indicating highway legends and characters, comprising a flexible body including a plurality of sections, means for pivotally connecting said sections for relative transverse adjustment, and light reflecting elements carried by said sections at the location of said means for pivotally connecting said sections, each of said sections being provided with perforations at its opposite ends and the means for pivotally connecting said sections comprising studs carried by said light reflecting elements and passing through the perforations of adjacent links.

9. A marking strip for forming and indicating highway legends and characters, comprising a flexible body including a plurality of sections, means for pivotally connecting said sections for relative transverse adjustment, and light reflect-

ing elements carried by said sections at the location of said means for pivotally connecting said sections, at least some of said sections being provided with medial perforations for the passage of supporting elements.

10. A reflector sign, comprising a supporting panel, a plurality of reflector button housings, a reflector button disposed in each of said housings with its axis substantially perpendicular to said panel, each of said housings being provided with a pair of ears projecting laterally outward from the housing generally perpendicular to the axis of the button therein, the ears on each housing being spaced from each other angularly about the button-axis and provided with perforations near their outer extremities, said housings being serially arranged in predetermined pattern on the face of said panel with the ears of each button overlapping the ears of adjacent buttons and with the perforations in overlapping ears in alignment, and means for securing said housings to said panel, said means including members extending through said aligned perforations and into said panel.

25 11. A reflector sign, comprising a supporting panel, a series of links arranged serially in predetermined pattern on the face of said panel, a reflector button mounted in an intermediate position on each of said links, each of said links being provided with perforations at its opposite ends, the perforations in each link being respectively aligned with perforations in the ends of adjacent links, and means for securing said links to said panel, said means including members extending through said aligned perforations and into said panel.

30 12. The invention set forth in claim 11 with the addition that each of said buttons is mounted in a housing, said housings being in turn mounted in the respective links.

OKLA H. HERSHMAN.
